HIS ATTORNEY

UNITED STATES PATENT OFFICE.

WILLIAM E. MAULDIN, OF LOS ANGELES, CALIFORNIA.

LOCK.

Application filed July 8, 1918. Serial No. 243,778.

To all whom it may concern:

Be it known that I, WILLIAM E. MAULDIN, a citizen of the United States, residing at Los Angeles, in the county of Los Angeles 5 and State of California, have invented new and useful Improvements in Locks, of which the following is a specification.

This invention relates to locks and more particularly to combination locks, or locks 10 requiring certain relative readjustments of members before unlocking operation, and it has for its object to provide an improved lock of the general nature stated which will be superior in point of relative simplicity 15 and inexpensiveness of construction and organization, taken in connection with positiveness and reliability in action, proof against tampering, compactness in form and neatness in appearance, and which will be 20 generally superior in reliability and serviceability.

A further object of the invention is to provide a combination lock which is susceptible of adaptation for use in connection with a 25 wide variety of means, mechanisms and devices, to prevent the unauthorized use or operation of the same, as well as being useful in the usual fields where other locks are ordinarily employed, as for safes, safety 30 deposit boxes, doors and the like.

Another object is to provide a telltale means operable upon a wrong adjustment of the permutable parts to indicate the same and to remain in indicating position until 35 the correct permutation is made.

In the preferred embodiment of the invention, a longitudinally movable lock control element is provided, and a plurality of rotatable circular members each having a 40 notch adapted for registration with a lateral projection or stump on the lock control element are mounted transversely thereto and preferably spaced apart about the longitudinal axis of the lock control element and in 45 a common plane; such members are preferably mounted on suitable stems ranging parallel with the lock control element in a suitable casing, and such stems project through suitable apertures in the front wall 50 of the casing, the projecting end of each stem being provided with a knob or finger grip; the lock control element is likewise provided at its projecting end with an op-

erating knob or grip. When the device is in locked position the preferably circular 55 members prevent or block longitudinal movement of the lock control element, but when the circular members are turned, through their respective stems, so that proper registration of stump and notch is provided for, 60 the lock control element is unlocked and may be moved longitudinally in the casing, so rendering the device operative or permitting access to the safe, box or the like, as the case may be. A toothed wheel may be 65 provided on each stem, and a spring click arranged to engage each such toothed wheel, whereby authorized persons knowing the combination of a particular lock, may, by counting the audible clicks produced by the 70 springs, turn each circular member to its position of notch and stump registration, a stop device co-acting with each circular member determining the starting point in turning such members to make the proper 75 combination. Furthermore, one or more of the stems carrying the circular members may be provided with a co-acting telltale control element which is in operable position while the lock control element is in locked position and which becomes inoperative only 80 upon proper manipulation of the lock control element.

With the above and other objects in view, the invention consists in the novel and useful provision, formation, combination, association and relative arrangement of parts, members and features, all as hereinafter described, shown in the drawing, and finally 85 pointed out in the claim.

In the drawing:

Figure 1 is a front elevation of locking means constructed and organized in accordance with the invention, the same being shown as applied to a motor vehicle at the 95 instrument board or dash thereof;

Figure 2 is a vertical sectional view through the instrument board, taken on the axis of Fig. 1, and looking from the left, the locking means being shown in elevation; 100

Figure 3 is a longitudinal vertical sectional view of the locking means, taken through the plane of the axis of Figure 1, and looking from the right, the view being upon an enlarged scale; 105

Figure 4 is a transverse sectional view

taken upon the line x^4-x^4 , Figure 3, and looking in the direction of the appended arrows;

Figure 5 is a transverse sectional view taken upon the line x^5-x^6 , Figure 3, and looking in the direction of the appended arrows;

Figure 6 is a transverse sectional view taken upon the line x^6-x^6 , Figure 3, and looking in the direction of the appended arrows; and

Figure 7 is a fragmentary transverse sectional view taken upon the line x^7-x^7 , Figure 3, and looking in the direction of the appended arrows.

Corresponding parts in all the figures are designated by the same reference characters.

Referring with particularity to the drawing, in the embodiment of the invention 20 therein shown, A designates a casing, B designates a lock control element, C designates, in each instance, means to prevent the operation of the lock control element, D designates, in each instance, indicating means, 25 E designates a tell-tale controlling means, F designates alarm means controlled thereby, and G designates controlling means for vehicle motive means controlled by the lock control element which in the present instance 30 takes the form of a switch controlling the ignition circuit of an internal combustion engine.

The casing A is shown as comprising a tubular body 8 having an integral front 35 wall 9 which is shown as provided with a securing stud 10 by means of which and a nut 10^a the lock may be secured to a vehicle dash, and a rear end wall 11 which is shown as threaded into the tubular body 8, as at 11^a.

40 The lock control element B comprises a longitudinally movable and preferably rotatable shaft 12 having one end 12^a bent to form an electric switch bar and provided at its other end with a finger grip 12^b by means 45 of which the lock control element may be manipulated, and a member 13 preferably rotatably mounted upon the shaft 12 but prevented from endwise movement thereon by means of an enlargement 12^c of the shaft and 50 the grip 12^b between which enlargement and grip the member 13 is mounted. The member 13 is preferably formed with a body portion 14^a from which project a plurality of radial vanes 14^b which extend along the 55 body portion a part of its length, the shank 14^c of the body portion between the vanes and the grip 12^b being preferably in the form of a square rod as shown in Fig. 2 and being extensible through a square aperture 60 9^a (Fig. 3) in the front wall 9 of the casing. This square shank prevents rotation of the member 13 with the shaft 12.

65 The means C each comprise a rotatable disc 15 having a notch 15^a in its periphery, and a stem 15^b suitably journaled in the

front wall of the casing through which it extends and journaled in partitions 16 and 17 which are positioned transversely in the casing as by means of a set screw 19 passing through the casing and through one of the 70 bridges 18 by means of which the partitions 16 and 17 are united and held in proper spaced relation. A collar 15^b is provided on each stem 15^b so that the respective disc 15 may be confined between such collar and the 75 partition 16, the discs being frictionally secured to the stems in any well known or other suitable manner so that ordinarily each disc will rotate with its stem, but when the vanes 14^b are in the notches of the discs, 80 the discs will be held against rotation thereby, but the stems may be rotated. Each disc is provided at a point on its periphery with a projecting finger 15^c which is adapted for engagement with a pin 20 fitted into a hole 85 21 provided in the partition 16 near the periphery of the respective disc. A plurality or series of such holes 21 are provided at the periphery of each disc, so that the pins may be moved from hole to hole to effect 90 changes in the combination when required, and to provide for different combinations in the manufacture of the locks.

The means D comprise a wheel 22 provided with peripheral teeth 22^a, and a spring click or detent 23, which detent is preferably mounted on the partition 17 as by a pivot screw 24. Each detent is shown as of arcuate formation at its one end as at 23^a where it bears upon the shaft enlargement 12^c and as terminating in a tooth engaging point 23^b at its other end. Each wheel 22 is fixedly secured to one of the stems 15^b so that when such stem is rotated through its finger piece or knob 15^d provided on the stem externally of the casing the extent of the arc of rotation of each stem and disc 15 may be gauged by the operator as by "feeling" or by counting the audible clicks.

A tell-tale controlling means E comprises the cam or finger 25 provided on one of the stems 15^b where such stem projects through the partition 17, and a switch bar 26 pivoted in the plane of rotation of such finger, as by a screw pivot 26^a. The switch bar 26 is in the form of a bellcrank lever and is slightly bent so that it is frictionally retained in any position of adjustment by the partition 17 and its long arm is adapted for engagement with an electrical contact 27 to close 100 an alarm circuit, while its short arm is formed like a cam and is adapted to ride upon the enlargement 12^c of the shaft 12 when the lock is in unlocked or working position. The shaft 12 being reduced rearwardly of the enlargement 12^c and gradually merging therewith as by a tapered portion 12^d permits the alarm lever or switch to be thrown when the lock control element B is 105 in locked position, but throws off the alarm 110 in unlocked position.

switch upon movement of the lock control element B to unlocked position, as by causing the short arm or cam portion of the tell-tale control element to ride up the tapered shaft portion onto the enlargement when the shaft is moved inwardly of the casing. This switch bar and operating means therefore constitutes the tell-tale control element which may control any suitable alarm or signal means.

The alarm means F, for example, is shown as an electric bell mounted upon the closure and between the same and a partition 28 of insulating material spaced from the closure as by posts 11'. Upon the partition 28 is mounted the contact 27 in the path of movement of switch bar 26.

The ignition circuit controlling means G is shown as a plurality of electrical circuit 20 wires 29 and 30, extending, respectively, from a battery, not shown, and a magneto, not shown, to contacts 29^a and 30^a, respectively, mounted upon the partition 28 and in the path movement of the switch bar 12^a 25 when such switch bar is moved into operative position by operation of the lock control element B. The opposite sides or terminals of both the battery and magneto may be "grounded" to the vehicle frame with 30 which the casing A is also electrically connected as will be understood by persons skilled in this art. A shunt circuit wire 31 is connected with the battery circuit wire 29 and extends through the electric bell and 35 such shunt wire terminates at the alarm contact 27. The contacts 29^a and 30^a are each spaced at one side of the switch bar 12^a so that rotation of the switch bar in one direction will complete the battery circuit and 40 rotation of the switch bar in the opposite direction will complete the magneto circuit.

The operation, method of use and advantages of the invention will be readily understood from the foregoing disclosure, taken 45 in connection with the accompanying drawing and the following statement:

When the driver of a motor vehicle desires to lock the electrical circuits controlling the motive means, the lock control element 50 B is retracted by pulling on the finger grip thereof and so removing the switch bar 12^a from the plane of the contacts 29^a and 30^a. The vanes 14^b slide through the notches 15' in the discs 15 and after such passage of 55 the vanes therethrough the discs may be turned by turning their stems through the knobs 15^d and so blocking inward movement of the lock control element. In order to start the motor vehicle, it will be necessary 60 to know the combination and turn each disc, through its knob and stem until the peripheral finger 15^e thereon strikes the respective pin 20 and then reverse the direction of disc rotation, counting the clicks 65 of each spring detent 23, until the proper

number of clicks indicates that the respective disc has its notch 15' in registration with the respective vane 14^b on the element B. When each disc notch 15' is in registration with the vane 14^b the bolt may be moved 70 inwardly and the switch bar 12^a turned into engagement with either battery or magneto contact as desired. The frictional engagement of each stem and disc permits rotation of the stem knobs without disturbing 75 the switch bar when the control element is in its innermost position.

In case of tampering by unauthorized persons, there is a liability of operating the tell-tale control element and setting off the alarm, as by turning the tell-tale actuating stem in the wrong direction the cam or arm thereon will move the member 26 so that it will lie against the contact 27 and cause the ringing of the bell until the combination is 80 properly made and the lock control element pushed inwardly, whereupon the cam of the tell-tale control element will ride up the tapered shaft portion to the enlargement 12^e and so remove the member 26 from the 85 contact and break the bell circuit. Due to the adjustable pin arrangement whereby each pin may be positioned in any hole desired, of the respective series, an almost infinite variety of combinations may be had, 90 and a certain disc may be turned clockwise from its starting point as determined by its pin setting and the contact of its peripheral finger with the pin, while the remaining discs may be turned counter-clockwise from 95 their respective starting points.

It will be understood that many variations and departures from the specific disclosure herein may be made in adapting the invention to varying conditions of use and 100 service without departing from the spirit of the invention and the terms of the following claim.

It is also to be understood that the lock control element and tell-tale control element 110 are not limited to an electrical control as shown but may be connected for mechanical, pneumatic or any other well known means of control in a manner well understood by those skilled in the art.

Having thus disclosed my invention, I claim and desire to secure by Letters Patent:

In a combination lock, a longitudinally movable lock control element, means for blocking longitudinal movement of the lock 120 control element, comprising a plurality of permutation disks interposed in the path of a part of the lock control element and each having a notch arranged therein to permit movement of the lock control element when the disks are rotated into a predetermined position, means for setting the disks at a predetermined angular displacement in a given direction from said predetermined unlocking position, means hid- 125 130

den from sight for gauging the amount of rotation of the disks, and means for rotating said disks engaging the disks with sufficient friction to normally operate the same but insufficient to prevent movement of the rotating means when the disks are positively held against movement by said setting means.

In testimony whereof, I have signed my name to this specification in the presence 10 of two subscribing witnesses.

WILLIAM E. MAULDIN.
